(57) **CLAIM**

The ornamental design for a ball handle for a handheld tool, as shown and described.

DESCRIPTION

FIG. 1 is a top perspective view of a ball handle for a handheld tool of the present invention;

FIG. 2 is a magnified perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The ornamental design which is claimed is shown in solid lines in the drawings.

The broken lines are included for the purpose of illustrating portions of the article and form no part of the claimed design.
